UNITED STATES PATENT OFFICE.

CHARLES E. SEABURY, OF STONY BROOK, NEW YORK.

CAR-COUPING.

SPECIFICATION forming part of Letters Patent No. 429,365, dated June 3, 1890.

Application filed October 19, 1889. Serial No. 327,571. (No model.)

To all whom it may concern:

Be it known that I, CHARLES E. SEABURY, of Stony Brook, in the county of Suffolk and State of New York, have invented a new and 5 Improved Car-Coupling, of which the following is a full, clear, and exact description.

My invention relates to car-couplings, and has for its object to provide a simple, inexpensive, durable, and automatic coupling of 10 this character by which two cars may be coupled without requiring the train-men to go between them and expose themselves to injury. The coupling is adapted also to connect with the common link-and-pin draw-head. 15

The invention consists in certain novel features of construction and combinations of parts of the car-coupling, all as hereinafter described and claimed.

Reference is to be had to the accompanying drawings, forming a part of this specification, in which similar letters of reference indicate corresponding parts in all the figures.

Figure 1 is a vertical longitudinal sectional elevation of portions of two cars coupled by my improved coupling. Fig. 2 is a plan view thereof in horizontal section on the line xx in Fig. 1. Fig. 3 is a sectional side view of one coupler, illustrating how the coupling-pin is supported prior to coupling two cars; and Fig. 4 is a top perspective view of the spring-held link-block-coupler device.

The draw-head A of my improved coupling has a central cavity or chamber, in which the 35 link-block-coupler device B is held by a coupling-pin C. The draw-head has the usual flaring or bell mouth, and is preferably cast in one piece of metal, and may be sustained in position on the car-body D by any suitable 40 supports supplemented by buffer and draw springs fitted in the usual or any approved manner. The floor of the draw-head cavity is preferably convexed longitudinally at a at its front portion to allow the link-block coupler B to rock or have vertical play, so as to 45 rise and fall at its forward link or coupling end to accommodate or enter a draw-head of different height on an opposing car.

The coupler device B consists of a rear 50 block portion E, having a hole e to receive the coupling-pin and a front link portion F,

through which the coupling-pin of an opposing car will fall. This coupler device is preferably forged solid from one piece of wrought metal; but it may be made of cast-steel, if 55 desired. To the coupler-block E are secured three springs H H I. The springs H H are fastened at their rear ends to the back end of the block and extend forward and outward at either side thereof; but the spring I is fastened 60 to the block at its forward end and extends rearward and upward and rests at its free end against the top or roof of the draw-head cavity, while the two springs H H bear by their free ends upon opposite side walls of 65 the cavity. The three springs thus normally support the entire coupler device E F centrally, both vertically and horizontally, in the draw-head, while allowing ample play up, down, or sidewise to the outer link portion F 70 to accommodate the vertical or horizontal oscillations of the coupled cars.

Within the draw-head cavity and at one side thereof is hinged in any approved manner—by a pin j , for instance—a coupling-pin 75 support J, which has a vertical wall or part adapted to fit into a recess a' , made in the side wall of the draw-head, when the support is pushed inward by the advancing link to effect a coupling, as presently explained. 80 This support has an upper ledge portion c , onto which when swung forward the coupling-pin C will rest, as shown in Fig. 3 of the drawings.

While any suitable spring device may be 85 employed to normally throw the coupling-pin support forward into position to thus sustain the pin, I prefer to dispense with springs for this purpose and to provide at the inner face of the side wall of the draw-head a cavity a^2 , 90 into which a man's finger may be passed behind the support to easily draw it forward into position to sustain the pin, and I also provide a hole a^3 through the side of the draw-head to allow a bar or rod or push-pin 95 device to be inserted from the outside for forcing the coupling-pin support forward to sustain the pin should the support be stuck fast within the draw-head recess a' , so that it 100 cannot easily be drawn forward by the finger of a man's hand thrust into the draw-head cavity from the front.

The operation is very simple and effective, as follows: We will suppose two cars to be coupled are provided with my draw-head A, coupling-pin C, and pin-support J. Into one of the two opposing draw-heads the coupling-link block E F will be placed and held by a coupling-pin C, as shown in Figs. 1 and 2 of the drawings. The pin C of the other coupler will be sustained on the drawn-forward pin-support J, as shown in Fig. 3 of the drawings and as would be indicated also by the dotted position of the support in Fig. 2, and as the two cars come together the link F will enter the opposing draw-head and strike the pin-support J and push it backward, and the pin C, which it had sustained, will fall through or within the link and automatically couple the cars without requiring train-men to stand between them and expose themselves to injury.

15 Should the car draw-head holding the link device be higher or lower than the draw-head of the opposing car, the link may be set lower or higher, and the pressure of the side springs H H will so hold it to properly enter the other draw-head and effect the coupling. Any car provided with the block-link device E F may easily be coupled to another car having the common link-and-pin draw-head.

20 Having thus described my invention, I claim as new and desire to secure by Letters Patent—

25 1. In a car-coupling, the combination, with the draw-head, of a link-coupler device placed loosely therein and provided with side springs and a top spring bearing, respectively, on the

opposite sides and top of the draw-head cavity, and a coupling-pin passed through the draw-head and link device, substantially as herein set forth.

2. In a car-coupling, the combination, with a recessed draw-head, of a block-link E F, having a hole e and provided with opposite side springs H H and a top spring I, and a coupling-pin C, passed through the draw-head and the link-block hole e, substantially as described, and for the purposes set forth.

3. In car-couplings, the coupler device consisting of a rear block E, having a hole e for the coupling-pin and a front link F and provided with opposite side springs H H and a top spring I, substantially as herein set forth.

4. In a car-coupling, the combination, with a draw-head recessed interiorly at one side, of a hinged coupling-pin support adapted to said recess, said draw-head also recessed at a^2 , next the free edge of the infolded pin-support, to allow the latter to be easily drawn forward by the finger from inside the draw-head, substantially as herein set forth.

5. In a car-coupling, the combination, with a four-walled or inclosed draw-head, of a coupling-pin support hinged within it, said draw-head having a side hole or opening a^3 , allowing projection of the pin-support from outside the draw-head, substantially as herein set forth.

CHARLES E. SEABURY.
